Patented Dec. 8, 1914.

UNITED STATES PATENT OFFICE.

GEORGE C. KNAUFF, OF CHICAGO, ILLINOIS.

SWITCHING SOCKET OR CONNECTOR.

1,119,832.

Specification of Letters Patent. Patented Dec. 8, 1914.

Application filed December 12, 1913. Serial No. 806,240.

To all whom it may concern:

Be it known that I, GEORGE C. KNAUFF, citizen of the United States, residing at Chicago, in the county of Cook and State of Illinois, have invented certain new and useful Improvements in Switching Sockets or Connectors; and I do hereby declare the following to be a full, clear, and exact description of the invention, such as will enable others skilled in the art to which it appertains to make and use the same.

My invention relates to electric sockets and connectors and more particularly to the class of such devices equipped with a metal casing grounded to one terminal of the circuit and having the circuit closed through relatively contacting portions carried respectively by the socket and plug member of the appliance. In my co-pending application of even date herewith Serial No. 806,239, I have shown and described a socket or connector of this class equipped with a rotatable plug, which plug either closes or opens the circuit according to the position in which it is coupled to the casing. In the construction thus described, both the contacting and the pressure transmission between the socket and plug members are effected at a point considerably to one side of the common axis of the socket and the plug, thereby tending to cramp the plug and possibly interfering with the easy rotation of the plug between its normal coupled positions. Moreover, the construction shown in the said co-pending application requires a diameter which may be objectionable where the appliance is to be used in limited spaces, or where it is desirable to reduce the cost of construction by manufacturing the insulating parts out of rubber rods of smaller diameter.

The prime object of my present invention is to provide a construction in which the current-carrying members of both the socket and the plug are axially disposed, thereby permitting them to be mounted within insulating bodies of relatively small diameter; to provide means for effecting a double contact between the said conducting members of the socket and the plug, and for insuring an effective contact therebetween; and to provide a single spring member so disposed as simultaneously to effect the said contacting and to insure the secure coupling of the plug to the socket when in either its circuit-closing or circuit-opening positions.

Another object is to provide simple means for preventing a relative rotation of the contacting portions of the plug and socket.

Further objects will appear from the following description and from the accompanying drawings in which:

Figure 1— is a view partly in longitudinal section, of a lamp, socket and plug combination embodying my invention. Fig. 2— is a transverse section through Fig. 1— along the line 2—2. Fig. 3— is a fragmentary plan view of the right-hand end of Fig. 1—. Fig. 4 is a fragmentary sectional view showing a two-wire form of plug construction. Fig. 5— is a transverse section through Fig. 4— along the line 5—5. Fig. 6 is a longitudinal section through a separable wire connector embodying my invention. Fig. 7— is a transverse section through Fig. 6— along the line 7—7.

In the embodiment of Fig. 1—, my invention is shown as applied to a socket having a substantially cylindrical casing 1 grounded to the terminal 2 of an electric circuit, the said casing being equipped at its forward end with a pair of bayonet slots 3 diametrically opposite each other, the said slots receiving and interlocking with projections 4 upon the base of the incandescent lamp 5. Mounted within the casing 1 and rigidly secured therein is an insulating body 6 of hard rubber or other suitable material, carrying a metal tube 7 disposed axially of the insulating body 6 and the casing 1. Threadedly mounted upon one end of the cylinder 7 is a metal cap 8 having a contracted bore slidingly fitting the stem of a plunger 9, which plunger projects forwardly of the said cap into contact with one terminal of the lamp 5, the other terminal of the lamp filament being connected to the exterior of the casing 1 of the lamp and through the latter to the casing 1 of the socket. The plunger 9 has at its inner end an enlarged head 12 bearing continuously against a compression spring 13, the other end of which spring bears against the shank of a substantially Y-shaped flat metal punching 14. The cylinder 7 is secured to the insulated body 6 by a pin 15 extending transversely through the bore near one end thereof, the said pin passing also through an elongated slot 16 in the said shank of the Y-shaped member.

At its rear end the casing 1 is equipped with

diametrically opposite slot formations, each thereof comprising double-sided bayonet formations consisting of a pair of socket portions 18 disposed at points widely separated 5 circumferentially of the casing and connected by a slot portion 19 extending circumferentially of the casing, which circumferential portion 19 is connected by the main portion 17 of the slot formation with the end of 10 the casing. Each of the socket portions 18 of the said slots is adapted interchangeably to seat one of the lateral projections 20 upon a plug 21 so as to couple said plug to the casing in either one of two rotationally 15 separated positions. Mounted within the plug 2, which latter is preferably of hard rubber or fiber, is a wire-terminal 22 secured by a clamping screw 23 to the end of a wire 24, which wire forms the other terminus of 20 the said circuit. Threadedly connected to the forward end of the said terminal 22 is a substantially rectangular contact plate 25, preferably equipped along its longitudinal edges with beveled portions 26, the said plate resting 25 upon the forward face of the plug 21 and extending transversely of the said plug and of the casing 1. To prevent the said contact plate 25 from rotating with respect to the plug 21, I preferably punch one or 30 more prongs 27 in the said plate after it is mounted in position, the tips of the said prongs entering the body of the plug 21 to anchor the said plate against any tendency toward a rotary movement about the terminal 22.

When the plug and socket are coupled to each other in the position of Figs. —1— 2— and —3—, the arms or fork portions 28 of the Y-shaped member 14 bear against 40 the forward surface of the plug 21 radially outward of the lateral edges of the plate 25, so that the circuit is interrupted between the said plate and the said bifurcated member 12. Upon rotating the plug relatively 45 to the casing to interlock the projections upon the same with the other pair of sockets 18, the arms 28 of the bifurcated member will ride up the slopes 26 of the plate 25 and contact with the face thereof, as shown 50 in dotted lines in Figs. —2— and —3—, thereby closing the circuit. The shank of the bifurcated member 14 is preferably somewhat narrower in width than the bore of the cylinder 7, thereby permitting the 55 said bifurcated member to tilt with respect to the axis of the socket so as to insure a firm contact between both of the arms 28 and the plate 25. It will be obvious from the drawings that the single spring 13 will 60 simultaneously press the plunger 9 into forcible contact with the lamp terminal 10, and also press the arms 28 of the bifurcated member into forcible contact with the plate 25 when the plug is in the circuit-closing 65 position; also that the spring and the bi-

furcated member will co-act with the plug 21 when the latter is in either of its said coupled positions to hold the projections upon the said plug securely interlocked with the respective socket portions 18 of the slot 70 formations. It will also be evident that the plug 21 and the wire-terminal carried thereby may be entirely disconnected from the socket by rotating the plug to the intermediate position in which the projections 20 75 align with the main slot portions 17, thereby permitting the plug to be withdrawn longitudinally from the socket. Should it be desirable to provide a similar switching arrangement without providing for such a detaching of the plug, this can be provided by omitting the main portion 17 of the slot, as shown by dotted lines in Fig. —3—.

In the embodiment of Figs. —6— and —7—, my invention is shown as applied to 85 a separable wire connector comprising a casing 1 having a plug 29 rigidly secured near one end thereof, and a wire-terminal 30 mounted within the said plug and secured by a screw 31 to the end of a wire 32 90 forming one terminal of a circuit. The other end of the casing 1 is equipped with duplex bayonet slots similar to those of Fig. —3—, the said slots interlocking in either 95 of two rotationally separated positions with projections 20 upon a movable plug 33. Mounted within the said plug 33 is a terminal 34 secured by a screw 35 to the end of a wire 36 forming the other terminal of the said circuit. The forward end of the 100 said terminal 34 is radially enlarged into a tube which is slotted diametrically of the casing so as to present two arch-shaped ends at opposite sides of the said slot, as shown in Fig. —7—. Likewise the rear end of the 105 other terminal 30 is radially enlarged and bored out to house a compression spring 37, which spring bears at its forward end against a solid portion of the said terminal and at its rear end against the shank of a 110 substantially T-shaped contact members 38, the shank of which member is equipped with a longitudinal perforation. Extending through the said longitudinal perforation and through the body of the plug 29 and of 115 the terminal 30 near the rear end of the latter is a pin 39, which pin will engage the forward end of the said elongated slot to prevent the spring 37 from ejecting the T-shaped member from the said bore of the 120 terminal 30. When the plug 33 is interlocked with the casing 1 in one of its coupled 125 positions, the transverse portion 40 of the T-shaped member will extend along the axis of the said slot in the forward portion of the 125 terminal 34, while the ends of the said portion 40 will bear against the forward surface of the insulating plug 33, thereby opening the circuit between the said portion 40 and the said arched portions 41 of the ter- 130

5 minal 34. Upon rotating the plug to the other of its said coupled positions, the said transverse portion 40 of the T-shaped member will ride up the beveled edges of the 10 arched portions 41 and contact with the latter, being forcibly pressed thereagainst by the spring 37.

15 It will be obvious that when the plug 33 is in either of its normal positions the spring 37 and the T-shaped member will coact with the plug 33 and the projections 20 upon the latter and the bayonet catch formations 20 upon the casing 1 to maintain the plug securely interlocked with the casing.

20 16 It will also be obvious that the elements comprising my structure may be varied in many ways without departing from the spirit of my invention as shown in the appended claims, hence I do not wish to be limited to the particular details of construction herein disclosed. For example, instead of grounding one terminal of the circuit directly to the casing of the socket as shown in dotted lines in Fig. 1, both wires 25 25 may be secured to terminals carried by the rotatable plug, as shown in Fig. 4. In this case, one of the said wire terminals may be grounded by a screw 20 to a metal shell housing the forward end of the plug and 30 slidingly contacting with the casing of the socket, while the other terminal 22 may be connected to the contact plate 25 by a screw portion as shown in Figs. 4 and 5.

35 I claim as my invention:

35 1. In a socket or connector, the combination with a casing, of a pair of circuit terminals mounted therein and insulated therefrom, the mounting thereof permitting relative rotary movement of the said terminals 40 about the axis of the casing; the said terminals equipped at their adjacent ends with normally contacting tips, one of said tips being bifurcated, the said bifurcated tip straddling and being out of contact with the 45 other tip when the said terminals have been partially rotated about the axis of the casing.

50 2. In a socket or connector, the combination with a casing, of a pair of circuit terminals mounted therein and insulated therefrom, the mounting thereof permitting relative rotary movement of the said terminals about the axis of the casing; the said terminals equipped at their adjacent ends with normally contacting tips, one of said tips being bifurcated, the said bifurcated tip straddling and being out of contact with the other tip when the said terminals have been partially rotated about the axis of the casing, and spring means associated with the 55 casing and one of the said terminals for maintaining the said terminals in either their said contacting or their said non-contacting relation.

60 3. In a socket and plug combination, a plug, a substantially cylindrical casing

equipped with means for coupling the plug thereto in either of two rotationally separated positions, the said coupling means permitting the plug to be rotated relatively to the casing to move the plug from one to the other of its said positions; a circuit terminal carried by the plug and equipped with an elongated contact portion disposed upon the forward face of the plug transversely of the casing; and a second circuit terminal mounted within and insulated from the casing forwardly of the said plug and equipped at its rear end with a forked portion straddling the said elongated contact portion of the other circuit terminal when the plug is coupled to the casing in one of its said positions, the said disposition of the forked and elongated terminal portions causing the tips of the said forked portions to be brought into contact with the said elongated portion of the other circuit terminal when the plug is in the other of its said coupled positions.

4. In a socket and plug combination, a plug, a substantially cylindrical casing equipped with means for coupling the plug thereto in either of two rotationally separated positions, the said coupling means permitting the plug to be rotated relatively to the casing to move the plug from one to the other of its said positions; a circuit terminal carried by the plug and equipped with an elongated contact portion disposed upon the forward face of the plug transversely of the casing; a second circuit terminal mounted within and insulated from the casing forwardly of the second plug and equipped at its rear end with a forked portion straddling the said elongated contact portion of the other circuit terminal, when the plug is coupled to the casing in one of its said positions, the said disposition of the forked and elongated terminal portions causing the tips of the said forked portions to be brought into contact with the said elongated portion of the other circuit terminal when the plug is in the other of its said coupled positions; and a spring associated with one of the said terminals and pressing the said terminals into forcible engagement with each other when the plug is coupled to the casing in its last-named position.

5. In a socket and plug combination, a plug, a substantially cylindrical casing equipped at one end with means for coupling the plug thereto in either of two rotationally separated positions, the said coupling means permitting the plug to be rotated relatively to the casing to move the plug from one to the other of its said positions; a circuit terminal carried by the plug and equipped with an elongated contact portion disposed upon the forward face of the plug transversely of the casing; and a second circuit terminal

- mounted within and insulated from the casing forwardly of the said plug and equipped at its rear end with a forked portion straddling the said elongated contact portion of the other circuit terminal when the plug is coupled to the casing in one of its said positions, the said disposition of the forked and elongated terminal portions causing the tips of the said forked portions to be brought into contact with the said elongated portion of the other circuit terminal when the plug is in the other of its said coupled positions; the said casing equipped at its other end with means for coupling a lamp or wire-terminal plug thereto, the forward end of the said second terminal contacting with a contact terminal of the said lamp or wire-terminal plug when the latter is coupled to the casing.
6. In a socket and plug combination, a plug, a substantially cylindrical casing equipped at one end with means for coupling the plug thereto in either of two rotationally separated positions, the said coupling means permitting the plug to be rotated relatively to the casing to move the plug from one to the other of its said positions, a circuit terminal carried by the plug and equipped with an elongated contact portion disposed upon the forward face of the plug transversely of the casing; a second circuit terminal mounted within and insulated from the casing forwardly of the said plug and equipped at its rear end with a forked portion straddling the said elongated contact portion of the other circuit terminal when the plug is coupled to the casing in one of its said positions, the said disposition of the forked and elongated terminal portions causing the tips of the said forked portions to be brought into contact with the said elongated portion of the other circuit terminal when the plug is in the other of its said coupled positions, the said casing equipped at its other end with means for coupling a lamp or wire-terminal plug thereto, the forward end of the said second terminal equipped at its forward end with a relatively movable portion contacting with a terminal of the said lamp or wire-terminal plug when the latter is coupled to the casing; and a spring carried by the said second terminal and interposed between the said forked and relatively movable portions thereof and simultaneously pressing the said portions into engagement respectively with the said elongated contact portion of the first-named wire-terminal and the said terminal of the lamp or wire-terminal plug.
7. In a socket and plug combination, a plug, a substantially cylindrical casing equipped with means for coupling the plug thereto in either of two rotationally separated positions, the said coupling means permitting the plug to be rotated relatively to the casing to move the plug from one to the other of its said positions, a circuit terminal carried by the plug and equipped at its forward end with a contact portion disposed upon the forward surface of the plug substantially transversely of the casing; and a second circuit terminal mounted within and insulated from the casing forwardly of the said plug; one of the said terminals being elongated transversely of the casing, the adjacent portion of the other thereof being forked and straddling the said elongated portion of the first-named circuit terminal when the plug is coupled to the casing in one of its said positions; the said shaping and disposition of the adjacent ends of the said terminals causing the tips of the said forked portion to be brought into contact with an elongated portion of the other terminal when the plug is in the other of its said coupled positions.
8. In a socket and plug combination, a plug, a substantially cylindrical casing equipped with means for coupling the plug thereto in either of two rotationally separated positions, the said coupling means permitting the plug to be rotated relatively to the casing to move the plug from one to the other of its said positions, a circuit terminal carried by the plug and equipped at its forward end with a contact portion disposed upon the forward surface of the plug substantially transversely of the casing; a second circuit terminal mounted within and insulated from the casing forwardly of the said plug; one of the said terminals being elongated transversely of the casing, the adjacent portion of the other thereof being forked and straddling the said elongated portion of the first-named circuit terminal when the plug is coupled to the casing in one of its said positions; the said shaping and disposition of the adjacent end of the said terminals causing the tips of the said forked portion to be brought into contact with an elongated portion of the other terminal when the plug is in the other of its said coupled positions; and a spring associated with one of the said terminals and pressing the adjacent ends thereof into forcible engagement with each other when the plug is in its last-named coupled position.
- In testimony whereof I have signed my name in presence of two subscribing witnesses.
